Attorney

UNITED STATES PATENT OFFICE.

HANS L. SONDERUP, OF ST. PAUL, NEBRASKA.

ATTACHMENT FOR STACKER TEETH.

Application filed June 12, 1925. Serial No. 36,710.

To all whom it may concern:

Be it known that I, HANS L. SONDERUP, a citizen of the United States of America, and resident of St. Paul, in the county of Howard and State of Nebraska, have invented certain new and useful Improvements in Attachments for Stackers Teeth, of which the following is a specification.

This invention relates to agricultural implements, and particularly to improvements in stacker teeth, the said invention having for an object the provision of novel means for holding material on the stacker tooth while it is being operated to elevate the load or to otherwise carry it.

It will be understood that the invention is applicable to stacker teeth which are intended for use in moving hay, straw and other stalks, and as the inventor does not wish to be limited, of course, with respect to its use, in the further description of the invention it will be referred to as operating on "hay," which term is intended to include any of the loads which stacker teeth are intended to transfer.

As a unit embodying the invention will be associated or applied to the end of each stacker tooth, a description of one of the units will suffice as a disclosure of the invention for the understanding of one skilled in the art.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in side elevation of a fragment of a stacker tooth with a device embodying the invention applied thereto;

Figure 2 illustrates a longitudinal sectional view with the guard elevated;

Figure 3 illustrates a similar view with the guard in its lowermost position; and

Figure 4 illustrates a sectional view of the device on the line 4—4 of Fig. 2.

In these drawings, 5 denotes a stacker tooth having a metallic projection which may be termed a "prong" applied to its end, and the said prong preferably com-

prises a plate 6 with side flanges 7 and 8 which embrace the stacker tooth near its outer end, and it may be secured thereto by fastenings 9 such as rivets or the like that extend transversely through the flanges and the stacker tooth. At the outer end of the prong the plate is looped and terminates in an inclined end 10 which lies on beveled ends of the flanges 7 and 8 to provide an inclined surface over which hay is moved when applied to the stacker tooth.

As a means for preventing dislodgment of the hay from the stacker tooth when the stacker tooth is being moved, a guard 11 is pivoted between the flanges 7 and 8 near their outer ends, the said guard having its outer end lying under the inclined end 10. The guard includes flanges 12 and 13 which are mounted on a pivot 14 at the outer end of the guard and the guard is capable of oscillating from the position in which it is shown in Fig. 2 to the position in which it is shown in Fig. 3, the purpose being that when hay is being delivered to the tooth the pressure incident to the application of the hay to the tooth will cause the guard to assume the position in which it is shown in Fig. 3, whereas when the hay has passed the guard, it will assume the position shown in Figs. 1 and 2, in which position it will prevent the hay from being dislodged from the end of the tooth.

It will be understood that the weight of the hay and pressure incident to its delivery to the tooth will depress the guard, and, in the present embodiment of the invention, as a means for returning the guard to the position in which it is shown in Figs. 1 and 2, springs 15 have their ends anchored to the pivot 14 and to a member 16, which latter is movable in slots 17 and 18 formed in the flanges 7 and 8, respectively. As here illustrated, the member 16 comprises a rod or bolt 19 having a bushing 20, which bushing rotates as it travels in the slots 17 and 18 and the springs 15 have their ends connected to the bushing.

A link or prop 21 has one of its ends connected to the element 16 and its opposite end partially rotatable on a pin 22 anchored to the flanges of the guard and as the member 16 slides in the slots 17 and 18 under the influence of the weight of the hay, the action of the link or prop 21 is such that it permits the guard to be depressed, whereas when the weight of the hay is removed from the

guard, the spring will pull the element 16 and the link or prop will then force the guard upwardly into the position in which it is shown in Figs. 1 and 2, where it will be held to prevent the dislodgment of hay from the tooth.

I claim:

1. In an attachment for stacker teeth, an element projecting from the end of a stacker tooth and connected thereto, a guard having its outer end pivotally connected to the element, yieldable means for moving the guard and holding the said guard elevated with respect to the element and operative to be depressed by the weight of the load passing over the guard, and means for arresting the guard in its outward movement to prevent said guard passing a position at right angles to the axis of the element.
2. In an attachment for stacker teeth, an element secured to and projecting from the end of a stacker tooth, said element having an inclined outer end, a guard having its outer end pivotally mounted in proximity to the end of the element, means for holding the guard with its end remote from the pivot diagonally with respect to the load receiving surface of the tooth, the said means being yieldable to permit the guard to swing approximately parallel with the load receiv-

ing surface of the tooth when the load is being moved onto the tooth.

3. In an attachment for stacker teeth, an element comprising a plate having side flanges, the said plate and side flanges partially embracing the stacker tooth at its ends, means for securing the element to the stacker tooth, the said flanges having longitudinally extending slots, an element slidable in the slots, a guard having its outer end pivotally connected to the flanges, a resilient element for drawing the member outwardly in the slots, and a link pivotally connected to said member and to the guard.

4. In an attachment for stacker teeth, a plate having side flanges secured to the outer end of a stacker tooth, the side flanges having slots therein; a member extending from one flange to the other and movable in the slots; a guard, a pivot in the flanges and the outer end of the guard whereby the guard is pivotally connected to the flanges, springs connecting the pivot of the guard to the member in the slots, and a link pivotally connected to the member and to the guard for holding the guard normally in an inclined position, as and for the purpose described.

HANS L. SONDERUP.
